US0D1073227S

(12) **United States Design Patent** (10) Patent No.: **US D1,073,227 S**
(45) Date of Patent: ** Apr. 29, 2025

(54) **CONTROL PANEL FOR WASHING MACHINE**

(71) Applicant: **LG ELECTRONICS INC.**, Seoul (KR)

(72) Inventors: **Yejí Um**, Seoul (KR); **Hoil Jeon**, Seoul (KR); **Youngsoo Ha**, Seoul (KR); **Kyutae Park**, Seoul (KR)

(73) Assignee: **LG ELECTRONICS INC.**, Seoul (KR)

(**) Term: **15 Years**

(21) Appl. No.: **35/520,103**

(22) Filed: **Feb. 23, 2023**

(80) **Hague Agreement Data**

Int. Filing Date: **Feb. 23, 2023**

Int. Reg. No.: **DM/227352**

Int. Reg. Date: **Feb. 23, 2023**

Int. Reg. Pub. Date: **Feb. 23, 2024**

(30) **Foreign Application Priority Data**

Oct. 5, 2022 (KR) 30-2022-0040720

(51) **LOC (15) Cl.** **15-05**

(52) **U.S. Cl.**

USPC **D32/28**

(58) **Field of Classification Search**

USPC D10/49; D13/162, 184; D32/2, 3, 6, 25,
D32/28

CPC D06F 33/00; D06F 33/30; D06F 33/50;
D06F 34/00

See application file for complete search history.

(57) **CLAIM**

The ornamental design for a control panel for washing machine as shown and described.

DESCRIPTION

1. Control panel for washing machine

1.1 : Front perspective

1.2 : Back perspective

1.3 : Front

1.4 : Back

1.5 : Left

1.6 : Right

1.7 : Top

1.8 : Bottom

1.9 : Reference

The broken lines shown in reproductions 1.1 to 1.8 depict portions of the control panel for washing machine and form

(Continued)

no part of the claimed design; reproduction 1.9 shows a state in use of the claimed design and portions shown in broken lines are disclaimed.

1 Claim, 9 Drawing Sheets
